C. P. COLE, SR

INDICATOR DEVICE

Filed July 30, 1924

WITNESS

W. M. Bell

INVENTOR

Charles P. Cole Sr.
John W. Townsend
ATTORNEY

UNITED STATES PATENT OFFICE.

CHARLES P. COLE, SR., OF PATERSON, NEW JERSEY.

INDICATOR DEVICE.

Application filed July 30, 1924. Serial No. 729,104.

To all whom it may concern:

Be it known that I, CHARLES P. COLE, Sr., a citizen of the United States, residing at Paterson, in the county of Passaic and State 5 of New Jersey, have invented certain new and useful Improvements in Indicator Devices, of which the following is a specification.

In playing the game of golf the player in 10 making a stroke is supposed to "keep his eye on the ball," as the expression is, the idea being that by so doing he will not only the more certainly and fairly hit the ball with the club head but will avoid movements 15 of his head and consequently of other parts of his body which will detract from the "form" of his swing and among other faults result in the ball, though fairly struck, being caused to spin, which produces a right-hand curve ("slice") or a left-hand curve ("pull") in its flight, so that the possible 20 distance or direction desired is not obtained. I have found in practice that this custom results in another fault, to wit, that the 25 player often strikes the ball with the club too high, and this causes the ball to be badly mutilated by the club head, especially if the club is one of the so-called "irons" and as usual presents a sharp edge where it approaches closest to the ground in the swing, and it sometimes causes an over hand spin of 30 the ball, which shortens its flight.

The object of this invention is to provide an indicator or sighting device, which may 35 be made and sold at little expense and which will not in any way interfere with the stroke, by the use of which the player may obtain the necessary sighting for his stroke and also avoid hitting the ball so high as 40 to mutilate it or spoil the shot. My invention to this end consists in a sighting piece adapted to be arranged to project from under the ball toward the player and having a sighting spot or other portion which the 45 player can see in driving and means for securing or anchoring the device in centered relation to the ball.

My invention has been illustrated herein 50 in connection with some form of supporting tee on which the ball is placed when the player makes certain strokes in the game (usually the first stroke off the tee of each hole of the course); but broadly it is not indispensable that any supporting tee be employed in association with it.

In the accompanying drawings, Fig. 1 is a side elevation of my device shown associated with a supporting tee of the peg type in frequent use;

Fig. 2 is a plan of said device and the peg; 60

Fig. 3 is a perspective view of the device itself;

Fig. 4 is a side elevation of a form of said device associated with the more commonly used sand tee; 65

Fig. 5 is a plan of what is shown in Fig. 4;

Figs. 6 and 7 each show a plan and side elevation of other forms of the device associated with a sand tee;

Figs. 8 and 9 are a side elevation (partly 70 in section) and a plan of a form in which the device embodies a supporting tee;

Fig. 10 shows in side elevation and plan another form in which the device embodies a supporting tee; 75

Fig. 11 shows a modification of what is shown in Fig. 10.

Referring, first, to Figs. 1 to 3, *a* indicates a supporting tee of the peg type, with, a conical head *a'* on which the ball *A* is 80 adapted to be supported, and a pointed shank *a*² to be driven into the ground. This in this instance affords a suitable medium to which to secure my device, which as shown in the mentioned figures consists of a strip 85 of sheet material *b* which may have one end enlarged, as at *b'*, and at the other end has a hole *b*² to receive the shank of the tee *a*; the latter end thus affords its securing means.

The enlarged end *b'* of the device *b* may be 90 coloured, as red, as indicated by the cross-lining, so as to be conspicuous to the eye of the player. The device is of such length that when it is attached to the peg and lies on the surface of the ground, extending 95 radially from the peg, its end *b'* will appear to the player (if his stance is correct) as close to a straight line between the player's eye and the periphery of the ball. In driving,

the player keeps his eye on the visible 100 projecting end *b'* of the device *b* instead of upon the ball, the result of which is that in making the stroke the ball is not struck too high but squarely on the face of the club.

The device is intentionally light in 105 weight so that should it be struck by the club it will not interfere with the stroke and for this reason it is provided with means, as its apertured end *b*², whereby it may be readily secured in that correct posi- 110

tion in which it is centered with respect to the ball, as well as lying flatwise with the indicator portion b' squarely facing the player.

- 5 In Figs. 4, 5, 6 and 7 instead of the peg type of supporting tee being shown a supporting tee made in the conventional way of sand or earth is indicated at c . In Figs. 4 and 5 the device of my invention is shown 10 as a strip d of sheet metal having one end enlarged and conspicuously colored, as at d' , and projecting downwardly therefrom is an anchoring shank d^2 , which may be a pin soldered to the underside of the strip. In 15 this case the shank is forced into the ground and the tee c is built up so as partly to cover the strip, leaving its end d' protruding so as to be sighted by the player as before. The only difference between the construction of 20 Figs. 4 and 5 and that of Fig. 7 is that in the latter case the device e , (having the conspicuously colored end e') and its shank e^2 are both made from a single strip of sheet metal having one end bent back and under 25 and then downward to form said shank; the difference in the construction of Fig. 6 over that in Figs. 4 and 5 is that in the former case the pin is absent, the securing means being afforded by the inner end f' of 30 the device f , which inner end is simply embedded in the tee. In all these cases the device is readily centered with reference to 35 the ball because it will be placed in radial relation to the tee c , its elongated shape serving to facilitate the centering.

- In Figs. 8 to 11 the device and the supporting tee are formed as a unitary element. In Figs. 8 and 9 a truncated conical shell g , of thin material inverted and with its closed 40 end recessed or dished somewhat at g' to afford a seat for the ball A, forms the tee portion and projecting from it is a tab g^2 which 45 may have a conspicuously colored portion as shown to be sighted by the player, the same projecting radially from the basal edge of the tee. In Fig. 10 there is a disk h having up-standing centrally from it a cup h' to 50 form the seat for the ball A, and this disk has projecting from its edge a tab h^2 which may be conspicuously colored, as shown, to be sighted by the player; Fig. 11 shows a construction which only differs from that last described in that depending centrally

from the disk is a pin h^3 to be driven into the ground. In Figs. 8 to 11 the centering 55 of the device with reference to the ball is of course due to the cup g' or h' being centrally located on the disk.

The device will be usually arranged by the player so that the indicator portion 60 will project from under that side of the ball which receives the impact of the club; or it may project toward the player. This is a matter of the individual choice of the player and is not of course material to the invention. 65

I claim:

1. A golf-ball sighting indicator consisting of a sighting piece adapted to be placed under the ball and project from under the 70 same into the line of vision of the player and having on the part so projecting a conspicuous indicator-portion visible by the player when the device is so positioned and also having means for securing it in centered relation under the ball. 75

2. A golf-ball sighting indicator consisting of an elongated piece adapted to be placed under the ball in position to project 80 radially from its vertical axis and from under the ball into the line of vision of the player and having a conspicuous indicator-portion visible by the player when the device is so positioned and means to secure it fixed in such position. 85

3. A golf-ball sighting indicator consisting of an elongated piece adapted to be placed under the ball in position to project 90 radially from its vertical axis and from under the ball into the line of vision of the player and having a conspicuous indicator-portion visible by the player when the device is so positioned and also having a depending anchoring shank. 95

4. A golf-ball sighting indicator consisting of a sighting piece adapted to be placed under the ball and project from under the same into the line of vision of the player and having on the part so projecting a conspicuous indicator-portion visible by the player when the device is so positioned and also having a recess forming a seat for the ball. 100

In testimony whereof I affix my signature.

CHARLES P. COLE, Sr.
